W. P. ALBERT

CONTROLLING SYSTEM

Filed May 11, 1921

Inventor:
Walter P. Albert.
by E.R. Nowlan Atty

UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

CONTROLLING SYSTEM.

Application filed May 11, 1921. Serial No. 468,478.

To all whom it may concern:

Be it known that I, WALTER P. ALBERT, a citizen of the United States, residing at East Orange, in the county of Essex, State of New Jersey, have invented certain new and useful Improvements in Controlling Systems, of which the following is a full, clear, concise, and exact description.

This invention relates to improvements in control circuits and more particularly to improved circuits for controlling the operation of a mechanical device which is operated in a step-by-step movement in response to impulses generated by some form of impulse sending mechanism.

Step-by-step mechanisms are well-known in the automatic telephone art, where they may be used either as switches to establish telephonic connections, as registers, as number indicating devices, or for performing a variety of functions as progression controlling apparatus and means for associating various pieces of apparatus with one another. In order to meet the requirements of the modern automatic telephone system, step-by-step devices which are operated under the control of impulse sending devices, must be capable of a high speed of operation. This means that the impulses generated in the controlling line succeed one another at a rapid rate. If the line is of considerable length it will have varying characteristics as regards its impedance and leakage. As a result, lines of various lengths will differ in their transmitting qualities, so that it becomes difficult to cause a fixed form of mechanism to respond uniformly under various conditions of line length. Local and temporary disturbances in proximity to the controlling line may also affect the transmission qualities of the line. A dial which has become imperfect due to wear or poor adjustment of the governor may also produce impulses of undesirable characteristics.

It is usual in systems in which step-by-step devices are controlled, to provide a relay which follows the pulses produced by the impulse generating device. If the various inductive and capacity effects are of sufficient strength it may happen that the pulses actually received by this relay are considerably distorted or mutilated, even though they are generated at a uniform rate. Thus, it would be possible that due to the

characteristics of the line, the impulse receiving relay might, upon deenergization, make a contact of very short duration with its back contact, and almost immediately be reenergized. Another set of conditions might result in causing the relay to be energized for only a very short interval of time.

Previous circuits have been devised, as for example, those shown in my copending application, Serial No. 378,100, filed May 1, 1920, Patent No. 1,499,573, March 27, 1923, in which the evil effects of distorted impulses may be overcome. My invention however, contemplates an improvement over such systems, in that it also overcomes to a marked degree the evil effect of line leakage in addition to insuring correct operation upon the receipt of mutilated pulses.

It is obvious that if sufficient line leakage is present the impulse receiving relay will have a tendency to remain energized after the contact break at the dial if the leakage occurs between the relay and the impulse sender, since this leakage tends to short-circuit the contacts of the sender.

It is the object of this invention to provide circuits for controlling the operation of the step-by-step mechanism, such that the switch will respond to mutilated impulses even on a line of considerable leakage without danger of losing synchronism with the sending device.

A feature of the invention is the use of a double wound impulse receiving relay, the two windings of which are provided with circuits, such that the windings at certain times magnetically oppose one another, while at other times the windings magnetically aid one another.

It is to be understood that the invention is not to be limited to the specific form disclosed, since it is capable of a wide variety of adaptions.

It is thought that the invention will best be understood from the following detailed description, reference being had to the accompanying drawing.

The drawing shows such portions of a controlling circuit and a step-by-step device controlled by an impulse sender as are necessary to an understanding of the invention.

For the sake of simplifying the descrip-

- tion, it has been assumed that the step-by-step device, indicated generally at 12, is a register switch to be positioned under the control of a subscriber's substation sender, indicated at 3. The operating portions of the register switch include a stepping magnet 8, a stepping pawl 9, a ratchet wheel 10, and a holding pawl 11. The operation of the system is as follows.
- 10 When the calling subscriber removes his receiver from the switchhook (not shown) the line circuit is completed and line relay 2 is energized over a circuit extending from grounded battery, resistance 1, right-hand winding of relay 2, through the switchhook contacts, impulse springs 13 and 14, thence over the other side of the line and through the right-hand winding of resistance coil 4 to ground. Relay 2 is energized in this circuit and completes a circuit from grounded battery, winding of slow-release relay 5, resistance 6, armature and front contact of relay 2 to ground. Relay 2 upon energization also completes a circuit through its left-hand winding from grounded battery, resistance 1, left-hand winding of relay 2, resistance 6, armature and front contact of relay 2 to ground. The direction of current flow in this circuit is such as to cause the 30 left-hand winding of relay 2 to magnetically oppose the right-hand winding of such relay, thus making the relay very quick to fall off when dial springs 13 and 14 are opened.
- When the dial springs are opened to send the first impulse, line relay 2 is deenergized and completes a circuit from grounded battery, winding of stepping magnet 8, winding of slow-release relay 7, armature and front contact of slow-release relay 5, which remains energized between impulses, and the armature and back contact of relay 2 to ground. Stepping magnet 8 and relay 7 are energized in this circuit. It should be noted that at this time the right-hand operating winding of relay 2 is completely short-circuited by ground at its own armature and back contact, this circuit extending through contact springs 15 and 16, controlled by the stepping magnet 8, through the armature and front contact of relay 5. If the sender should again complete the dial circuit before stepping magnet 8 has completed its stroke, relay 2 cannot be energized, due to the short circuit just traced. It is to be observed that 50 during the interval in which relay 2 is deenergized a circuit is in existence from grounded battery, winding of relay 5, left-hand winding of relay 2 and thence to ground, at the armature and back contact of relay 2, as described. Current flow in this circuit is not sufficient to cause the energization of relay 2, but is in a direction to cause the left-hand winding of this relay to magnetically aid its right-hand winding when 60 such winding is energized by the closure of

the dial springs. This makes the relay very quick to energize when the dial circuit is again completed.

When stepping magnet 8 has fully attracted its armature, contacts 15 and 16 are opened and allow line relay 2 to be energized upon the subsequent closure of the impulse circuit.

It is to be observed that if relay 2 receives a mutilated pulse of such character that the break in the impulse circuit is of very short duration, correct operation will take place nevertheless, because the right-hand operating winding of relay 2 is short-circuited until magnet 8 has caused the register to be advanced a full step.

If the impulses received by relay 2 are distorted in a manner such that the open condition of the impulse circuit exists for a longer time than normally, no harm can be done since relay 5 is positively prevented from releasing, since it has a circuit through the left-hand winding of relay 2, until the switch has advanced a full step. This additional holding circuit should provide ample time to prevent the release of the relay.

If the opened condition of the impulse circuit continues to exist after the switch has made a full step, the circuit for relay 5 will be opened at contacts 15 and 16 and slow-to-release relay 5 will be released after a predetermined time opening the circuits for the stepping magnet at the armature and contact of relay 5 thus allowing the stepping magnet to release.

The resistances and windings of the various relays in the circuit are so proportioned that the ampere-turn value of the left-hand winding of relay 2 is greater than the ampere-turn value of the leakage current in the winding. This produces a material reduction in the effect of line leakage on pulsing. Thus when the relay 2 is energized, the opposing effect of its left-hand winding overcomes the tendency of line leakage to hinder proper release of the relay.

It should also be observed that the effect of the left-hand winding of relay 2 is of greatest benefit when needed most, that is, when the dial circuit is closed before the magnet contact opens. In this case, the magnetic condition built up in the left-hand winding makes the relay very quick to operate and open the circuit of the stepping magnet.

What is claimed is:

1. In a controlling system, a step-by-step device, an operating magnet therefor, an impulse receiving relay, an operating winding for said relay, means for transmitting impulses over the circuit for said operating winding to actuate said relay, a second winding for said relay, control circuits, means to shift said control circuits so that at certain times said second winding magnetically opposes said operating winding to make

- said relay quick to release, and so that at other times said second winding magnetically aids said operating winding to make said relay quick to operate, and a circuit for 5 said operating magnet controlled by said relay.
2. In a controlling system, a relay, an operating winding for said relay, means to actuate said relay in response to impulses directed to said operating winding, and means for rendering said relay quick to operate upon the completion of a circuit through said operating winding, said means comprising a second winding for said relay, 10 a circuit for said second winding, and means to complete said circuit during the non-operated condition of said relay.
3. In a controlling system, a step-by-step device, an operating magnet therefor, an impulse receiving relay, an operating winding for said relay, a second winding for said relay, and a circuit for said second winding controlled at normal contacts of said operating magnet and of said relay, the magnetic relation of said windings being such 15 as to render said relay quick to operate when said second winding is energized.
4. In a controlling system, a relay, an operating winding for said relay, a second operating winding for said relay, circuits for said windings, means for transmitting impulses over the circuit for said operating winding to actuate said relay, and means for rendering said relay quick to energize at certain 20 times and quick to release at other times, said means including means to complete desired ones of said circuits at desired times to produce a variable magnetic relation between said windings.
5. In a controlling system, a step-by-step device, an operating magnet therefor, an impulse receiving relay, an operating wind- 25
- ing for said relay, a second winding for said relay, a circuit for said magnet controlled by said relay, and means to produce a variable magnetic relation between said windings to make said relay quick to operate at certain times and quick to release at other times, said means including a circuit controlled by said magnet for shunting said operating winding. 30
6. In a controlling system, a step-by-step device, an operating magnet therefor, an impulse receiving relay, an operating winding for said relay, a second winding for said relay, control circuits, and means to shift said control circuits so that at certain times said second winding magnetically opposes said operating winding and so that at other times said second winding magnetically aids 35 said operating winding, a circuit for said magnet controlled by said relay, said means including a circuit controlled by said magnet for shunting said operating winding. 40
7. In a controlling system, a line, a device for transmitting impulses over said line, an impulse receiving relay to be operated under the control of said sending device, and means to insure synchronism between said sending device and said relay under varying conditions of line impedance and line leakage. 45
8. In a controlling system, a step-by-step device, an operating magnet therefor, an impulse receiving relay, a slow-to-release relay, a circuit for said slow-to-release relay completed under the control of said impulse receiving relay in the energized condition of said impulse receiving relay, and an auxiliary circuit for said slow-to-release relay controlled jointly at normal contacts of said magnet and of said impulse receiving relay. 50

In witness whereof, I hereunto subscribe my name this 10th day of May A. D., 1921.

WALTER P. ALBERT.
